OPTICAL SYSTEM FOR SOUND
REPRODUCTION

Harold J. Hasbrouck, Jr., Flushing, N. Y., assignor to United Research Corporation, Long Island City, N. Y., a corporation of Delaware

Application July 24, 1935, Serial No. 32,862

7 Claims. (Cl. 179—100.3)

This invention relates to the reproduction of sound and particularly to the reproduction of sound from diapositive records wherein a light sensitive device is utilized for translating light variations into corresponding electrical variations.

An object of the invention is to increase the efficiency of translation of light modulations into electrical currents.

10 Another object of the invention is to transform variable area light modulations into variable density light impressions upon the light sensitive device.

15 A further object of the invention is to eliminate moving shadows over a light sensitive material having non-uniform response characteristics.

In the art of sound reproduction from linear carriers such as talking motion picture film, a constant light source projects a beam of light 20 defined by a slit on to a sound record of a film, the emergent light being impressed on light sensitive material in accordance with the varying transmission through the sound record. In the case of a variable area record, that is, one in 25 which the opaque portion varies in width in accordance with sound, shadows move back and forth over the light sensitive material in accordance with the opaque outline of the sound track. Since it is not possible to obtain a photo- 30 sensitive surface perfectly uniform over its entire area, the electrical energy output of the device will not exactly correspond to the light variations. Although this is true of any photo-sensitive device whether a photo-electric cell or 35 the varying resistance type of cell, it is particularly true in the case of a selenium cell wherein a large number of fine electrodes are interdigitated to form the light sensitive surface. As the shadows pass over the surface there may be a 40 slight variation in resistance of each alternate section of the electrodes, with the result that instead of a smooth variation in accordance with the movement of the light, a stepped variation may be obtained in the output of the cell.

45 The present invention eliminates any deleterious effects caused by these variations in resistance or response, by changing the light modulations as impressed on the cell from those of variable area to those of variable intensity. The cell is thus 50 completely illuminated in accordance with the amount or quanta of light passing through the sound track portion of the film with the result that all units of the cell add their response simultaneously to produce an over-all effect not subject to the total response of any particular unit.

The invention contemplates, therefore, a rectangular light source imaged in an objective lens which in turn images a rectangular slit upon the sound track portion of a film. A cylindrical lens on the opposite side of the film unidimensionally images the objective lens, in which the light source image lies, upon the light sensitive surface of a light sensitive cell, such as selenium. As this surface is substantially square and the beam of illumination passing through the film is rectangular, the cylindrical lens functions to reduce the beam to the desired dimensions.

The details of the invention will be more fully understood by reference to the following description read in conjunction with the accompanying drawing, in which

Fig. 1 is a cross-sectional view of the essential elements of the invention.

Fig. 2 is a perspective diagrammatic view of the elements of Fig. 1.

20 Figs. 3 and 4 are detail views of one type of photo-sensitive device which may be used in Figs. 1 and 2; and

Fig. 5 is a detail view of the section of the holder employed for an optical element and a 25 photo-sensitive device such as a selenium cell.

Referring now to Fig. 1, a lamp 4 of constant intensity projects light from a rectangular filament 5 through an optical assembly 6 having a condenser lens 8, a slit mask 9, cup-shaped members 10 for stiffening the assembly, and an objective lens 11. Emergent light from the assembly 6 is projected on the sound track portion of a film 12 positioned by a shoe 13 having an aperture 14 therein through which the light passes to a 30 cylindrical lens 16 and a photo-sensitive device in the form of a selenium cell 17.

Referring to Fig. 2, the essential elements of Fig. 1 are arranged in perspective to aid in explaining their relationship, the film 12 being 40 shown as having a variable area sound track 20 and the selenium cell 17 as having a light sensitive portion 21. Cell 17 is shown connected through an amplifier 23 to a sound reproducer 24.

In the operation of the above system, the light 45 from the filament 5 passes through the condenser lens 8, the slit of the mask 9 through the objective lens 11, the sound track 20, lens 16, on to the light sensitive surface 21 of the cell 17. The filament 5 is imaged in the objective lens 11 50 while the objective lens 11 images the slit 9 upon the sound track 20. In usual practice the cylindrical lens 16 is not used and the selenium cell 17 is positioned close to the film, the light sensitive surface 21 thus receiving moving shadows or 55

light according to the outline of the sound track 20 passing the aperture 14 of the shoe 13. Fig. 3 illustrates this condition by showing a shadow or light spot 26 which represents a unit length of sound track determined by the slot in mask 9. The dotted lines 27 and 28 represent different positions of the shadow 26 caused by different units of the sound track at the aperture 14. It is thus realized that as the shadow 26 passes 10 back and forth over the light sensitive surface 21 different amounts of the surface starting from the left hand side of the cell in Fig. 3 will be darkened and illuminated with the result that unless the variations in resistance of each 15 selenium strip making up the cell are equal to another for equal light intensities, the output of the cell will not be increased and decreased uniformly and smoothly as the shadows pass thereover but in non-uniform steps.

20 Returning now to Figs. 1 and 2, the selenium cell 17 is shown positioned back from the film with the cylindrical lens 16 interposed therebetween so as to image the objective lens 11 and the filament 5 appearing therein on the sensitive surface 21 in one direction only. Since the filament image appearing in the objective lens 11 is rectangular, it is only necessary to reduce the rectangular section in one direction to completely fill the light sensitive area with the light 25 as seen at the objective lens 11. In this manner the sound track functions as a variable stop or iris and varies the intensity of the light over the entire cell in accordance with the variations in opacity on the sound track portion which varies the quanta of light passing therethrough.

In Fig. 4 the area or beam of illumination on the cell is shown by the dotted lines 30 when the cylindrical lens is not used, the cylindrical lens compressing this rectangle into substantially a 40 square just covering the interdigitations constituting the sensitive area of the cell. Being completely illuminated, each individual section or unit of the cell will vary with the total illumination thereon, the final output of the cell thus 45 being the additive or cumulative reaction or response of each unit which will provide a uniform over-all effect.

In Fig. 5 a portion of the holder for supporting the cell 17 and the cylindrical lens 16 in 50 proper fixed relationship is shown as a section of insulating material 32 having an opening in which is positioned the cell 17, the front portion of which is maintained against the front wall of the opening by contact springs 18 to which 55 are connected the outgoing terminals. The cylindrical lens 16 is positioned in the front portion 33 and may be sealed therein, the front wall having an opening in line with the light sensitive surface of the cell 17. This holder is disclosed 60 and claimed in U. S. Patent No. 2,031,646 of Feb. 25, 1936.

It is to be understood that this invention is applicable to other photo-sensitive devices such as electrolytic or photoelectric cells of the caesium 65 or potassium type wherein it is desired to vary the intensity over the entire cell in preference to permitting modulations to impinge thereon as moving shadows over their light sensitive surfaces.

70 What is claimed is:

1. An apparatus for producing sound from a sound record on a film, comprising a light sensitive cell having an electrode of definite dimensions and shape, an objective lens for projecting 75 an image of an illuminated slit onto the sound

record on the film, said electrode being positioned to receive light rays which pass through portions of the sound record, a collective lens positioned between said objective lens and said cell, and a source of light rays having a definite size and 5 shape, said objective lens and said collective lens having such a shape and position with respect to the size and shape of said light source and the size and shape of said light sensitive cell that the image of said light source corresponds to the 10 light sensitive portion of said electrode.

2. An apparatus in accordance with claim 1 in which said collective lens is a cylindrical lens modifying the image of said light source in one 15 direction only.

3. A system of sound reproducing from a sound record on a film comprising a selenium cell having an active surface approximately square in shape, an objective lens for projecting an image of an illuminated slit onto the sound record of 20 said film, said active surface of said selenium cell being positioned to receive light rays which pass through portions of the sound record, a light source having a rectangular light emitting portion, and a collective lens positioned between 25 said objective lens and said cell and having a shape such as to distort the image of said light emitting portion of said light source to a size comparable to the size of the active surface of 30 said selenium cell.

4. In a sound recording system the combination of a light source having a rectangular light emitting portion, a light defining slit, a film having a sound track portion thereon, a lens intermediate said slit and said film for projecting an 35 image of said slit on the sound track portion of said film, a lens for imaging said light emitting portion of said light source in said objective lens, a light sensitive device having a light sensitive surface of different size and shape than the light 40 emitting portion of said light source, and a lens intermediate said film and said light sensitive device for re-imaging the light emitting portion of said light source on the light sensitive portion of said light sensitive cell with a size and 45 shape comparable to the size and shape of the light sensitive portion of the light sensitive cell.

5. A sound reproducing system in accordance with claim 4 in which said last mentioned lens comprises a cylindrical lens varying the image of 50 said light source in one direction only.

6. The method of obtaining variable intensity actuation of a light sensitive cell by a variable area sound record from a light source having a different size and shape than the size and shape 55 of the light sensitive portion of said cell comprising imaging the light source at a point intermediate the light source and sound track and re-imaging the light source upon the light sensitive surface while distorting the image to the 60 size and shape of the light sensitive portion of the light sensitive cell.

7. The method of actuating a light sensitive surface with variable density light variations with a variable area sound record, said light being 65 generated by a linear light source of different size and shape from that of said light sensitive surface comprising translating said linear light source into a light beam of rectangular cross section corresponding in size and shape to the 70 size and shape of said light sensitive surface and varying the intensity of said light beam without varying the size thereof by transversing a variable area sound record thereacross.
